(57) **CLAIM**

We claim the ornamental design for a barcode reading module, as shown and described.

DESCRIPTION

FIG. 1 is a front left isometric view of a barcode reading module according to the present invention.

FIG. 2 is a front right isometric view of the barcode reading module of FIG. 1.

FIG. 3 is a front view of the barcode reading module of FIG. 1.

FIG. 4 is a rear view of the barcode reading module of FIG. 1.

FIG. 5 is a top view of the barcode reading module of FIG. 1.

FIG. 6 is a bottom view of the barcode reading module of FIG. 1.

FIG. 7 is a left side view of the barcode reading module of FIG. 1; and,

FIG. 8 is a right side view of the barcode reading module of FIG. 1.
